UNITED STATES PATENT OFFICE

ERNEST G. DANN, OF CHICAGO, ILLINOIS

WATCH SUPPORT

Application filed August 13, 1925. Serial No. 50,065.

The present invention, relating, as indicated, to timing devices, is more particularly directed to an improved device provided both with a timepiece and means for using the same for indicating appointments and engagements, the length of interviews and the like, and also with a memorandum pad conveniently held for the making of such memoranda as may be desired during the course of a telephone or other conversation. The device is particularly intended for use by business and professional men. The principal object of the invention is the provision of a simple and inexpensive device which may be used for the purpose indicated and which shall be composed of few parts and shall conveniently relate an indicating timepiece and memorandum device.

To the accomplishment of the foregoing and related ends, said invention, then, consists of the means hereinafter fully described and particularly pointed out in the claim, the annexed drawing and the following description setting forth in detail certain mechanism embodying the invention, such disclosed means constituting, however, but one of various mechanical forms in which the principle of the invention may be used.

In said annexed drawing:—

Fig. 1 is a plan view of my device; Fig. 2 is a longitudinal cross-section through the same on the line 2—2, Fig. 1; Fig. 3 is a transverse section on the line 3—3, Fig. 1; Fig. 4 is a view similar to Fig. 3, but showing a modified form of device; Fig. 5 is a similar view showing still another modification; Fig. 6 is another view showing the device with a two-piece crystal; and Fig. 7 is a similar view showing another modification of the device.

Referring now to Figs. 1 and 2 there is shown a frame 1 provided with a rounded opening 2 in one end and with a flat support 3 extending from its center toward the other end and spaced from the portion surrounding the opening by a slot 4. The rounded head 5 of the frame may be conveniently provided with a slot 6, through which may be introduced the stem 7 of a timepiece 8 which may be clamped firmly against the underside 50 of a flange defining the rounded opening 2 by

means of a removable spring clip 9 which is secured by a screw 10 to a boss 11. The other end of the spring clip engages against the under side of the head of a memorandum pad 12, which may be slipped into the slot 4 while resting upon the supporting portion 3 of the frame. The timepiece 8 may be in the form of a watch of the usual size when the device is made in a small size, or it may be considerably larger if the entire device is increased in its size. In either event I provide a crystal 13, which is loosely mounted in a bezel 14 which holds the crystal in position over the dial of the timepiece, and is also provided with an indicating arrow or similar mark 30, which may be positioned at any point around the dial of the timepiece to mark either the time of beginning an interview, or may be positioned to note an appointment. This crystal may be readily positioned as may be desired around the dial by merely turning it with the finger as it is rotatably held in the bezel and is thus rotatable about the same center as the hands of the timepiece.

In Fig. 3 I have shown a transverse section of a modification of the above construction, in which the timepiece is provided with a fixed crystal 15 having a perforation opposite the axis of the hands, in which is rotatably held a shaft 16 provided with an adjusting nut 17 outside of the crystal and an indicating hand 18 within the same.

A similar construction in which both the hand and the adjusting or positioning nut therefor are mounted outside of the crystal are shown in Fig. 4, the shaft being rotatably mounted as before in the crystal and about the same axis as the axis of the hands of the timepiece.

A further modification of an indicating means for the timepiece is shown in Fig. 5, in which a crystal 20 is shown fixed in a bezel 21, the bezel being rotatably mounted on the case of the timepiece. The crystal carries an indicating hand or arrow, and by rotating the entire bezel and crystal any desired hour may be marked as before.

Other constructions are shown in Figs. 6 and 7. In Fig. 6 I have shown a double crystal, the lower crystal 22 being fixed, while

the upper crystal 23, which bears an indicating hand or mark, is rotatable over the lower crystal. In Fig. 7 an indicating ring is rotatably mounted in the flange of the frame in a position to rotate about the same axis as the hands of the timepiece, the ring carrying an indicating arrow 25.

All of the above constructions and others, which will readily suggest themselves upon examination of my improved device, may be 10 employed to secure the desirable function of noting any given hour on the timepiece, while the entire device may be employed either as a desk memorandum pad or it may be constructed for attachment to various other instruments and devices, such, for example, as a telephone to note the length of conversation, or for similar purposes.

Other modes of applying the principle of 20 my invention may be employed instead of the one explained, change being made as regards the structure herein disclosed, provided the means stated by the following claim or the equivalent of such stated means be employed.

I therefore particularly point out and distinctly claim as my invention:—

A desk facility comprising a shell of rigid material open at the bottom and providing a top plate and depending marginal flange, said flange having a slot open at one end and extending close to the top plate to receive the stem of a timepiece, the upper portion of said top plate having a circular opening defined by an inturned flange adapted to suitably 30 space a timepiece beneath said opening, a stud 35 provided at a central point beneath said top plate, a spring mounted on said stud and adapted to engage said timepiece to position the same with its dial exposed beneath said circular opening.

40 Signed by me, this 18th day of July, 1925.
ERNEST G. DANN.
